UNITED STATES PATENT OFFICE.

JOHN S. MITCHELL, OF MINNEAPOLIS, MINNESOTA.

CUFF LINK.

Application filed October 2, 1926. Serial No. 139,104.

This invention relates to improvements in cuff links and has for its objects to provide a very cheap one-piece device of flexible and elastic material, comprising terminal buttons integrally connected with and by an elastic link member elongatable by stretching, and adapted to so stretch, to allow the cuff to separate as the sleeve is pulled toward the elbow of the wearer.

10 Features of the invention include the one-piece construction of the device from rubber-like material.

Figure 1 is a sectional plan;

Figure 2 is a sectional elevation;

15 Figure 3 is an elevation, showing the link element stretched; and

Figure 4 is an end view.

The parts of the device may be proportioned in any desired manner, but the one-piece device comprises terminal button elements 1, 2, connected by a relatively thin band-like link element 3, all elements being composed of rubber-like material and the parts being integral. The link is thus adapted to stretch longitudinally to permit the cuffs to spread as they are pulled toward the elbow.

20 The use of rubber-like material permits the device to be moulded, and the material is colorable to provide a variety of attractive effects. Moreover, embossed or indented devices can be produced by moulding, upon the outer faces of the buttons, and even multi-colored effects can be obtained all by

a simple moulding process, and by the use 35 of a very cheap material.

If desired, the buttons may be vulcanized during or after formation to facilitate introduction through the buttonholes, although it has been found that sufficient stiffness 40 can be obtained by using a certain grade of stock, and giving the connecting link portion a small cross-sectional area, to provide for the proper longitudinal stretch.

The buttons can be moulded in various 45 shapes. No assembly of parts is necessary, as in the devices now in use; therefore the device can be very cheaply made. It is adapted for advertisement purposes, and can be produced from colored, rubber-like, 50 stretchable, materials.

I claim as my invention:

1. A device of the class described comprising a one-piece cuff link of rubber-like material having terminal buttons connected 55 by a single link element as a comparatively thin band, having a cross-section adapting it to be easily stretched lengthwise.

2. A device of the class described comprising a moulded one-piece cuff link of 60 rubber having terminal buttons connected by one link element as a comparatively thin band having a cross-section adapting it to be easily stretched lengthwise.

In witness whereof, I have hereunto set 65 my hand this 29th day of September, 1926.

JOHN S. MITCHELL.
